UNITED STATES PATENT OFFICE.

HARRY G. WEBSTER, OF CHICAGO, ILLINOIS, ASSIGNOR TO THE STROMBERG-CARLSON TELEPHONE COMPANY, OF ROCHESTER, NEW YORK, A CORPORATION OF NEW YORK.

TELEPHONE-EXCHANGE SYSTEM.

SPECIFICATION forming part of Letters Patent No. 775,226, dated November 15, 1904.

Application filed February 4, 1903. Serial No. 141,886. (No model.)

To all whom it may concern:

Be it known that I, HARRY G. WEBSTER, a citizen of the United States, residing at Chicago, in the county of Cook and State of Illinois, have invented a certain new and useful Improvement in Telephone-Exchange Systems, of which the following is a full, clear, concise, and exact description, reference being had to the accompanying drawing, forming 10 a part of this specification.

My invention relates to telephone-exchange systems, and more particularly to such systems in which a source of current located at the central station may be employed for the 15 purpose of supplying talking-current to substation-transmitters.

The principal objects of my invention are to provide a telephone-exchange system in which the complicated cut-off mechanism 20 heretofore employed may be dispensed with and a system having an improved means whereby the operator may test the operative condition of a subscriber's line.

A further object of my invention consists 25 in the provision of means whereby the disagreeable clicks produced in a subscriber's receiver, due to changes in the electrical circuits of the corresponding line, may be reduced.

I shall describe my invention by reference 30 to the accompanying drawing, in which are diagrammatically illustrated subscribers' substations A and B, connected each by limbs 1 and 2 of a telephone-line with a central ex- 35 change at C. Each subscriber's substation apparatus comprises a switch-hook 3, adapted when in its normal position to connect a signal-receiving means, such as the bell 4 and a condenser 4', in series with the limbs of the 40 telephone-line. When in its alternative or upper position, the switch-hook closes the line-circuit through a transmitter 5 and the primary 6 of an induction-coil, whose secondary 7 is connected with a receiver 8. The 45 receiver 8 when placed upon the switch-hook 3 is adapted to depress the hook in the manner well understood by those skilled in the art.

Each of the limbs 1 leads to the central ex-

change and there through the winding of a line-relay 9 to the negative pole of a common 50 battery 10, adapted to supply talking and signaling currents used in the operation of the system. The limb 1 from each substation is also permanently connected with the tip-springs 11 of an answering-jack 12 and multiple calling-jacks 13 13. The limb 2, running from each substation, is normally serially connected, through the differentially-wound coils 14 and 15 of the cut-off relay 16, with the positive grounded side of the common 60 battery 10. The common terminal of the relay-coils 14 and 15 is permanently connected with the sleeve-contacts 17 17 of the answering and multiple calling-jacks. These sleeve-contacts 17 17 also constitute the testing-thimbles 65 of the jacks.

The line-relay 9 is provided with an armature 18, adapted, when attracted by the relay 9, to close a local circuit from the battery 10 through the line-signal 19, which signal may 70 be in the form of a small incandescent lamp. The local circuit through this signal-lamp also includes an armature 20 of the cut-off relay, the attraction of this armature 20 from its back contact serving, however, to open the 75 circuit through the signal-lamp 19. The cut-off relay 16 is further provided with a second armature 21, adapted when attracted to short-circuit the winding 14 of the relay, thereby connecting the line-limb 2 directly with the 80 associated sleeve-contact 17 without the intervention of inductive resistance.

The operator's cord-circuit may desirably comprise answering and calling plugs 22 and 23, whose tip and sleeve contacts are respectively connected by the cord-strands 24 and 25. 85

The usual ringing and listening key 26 is provided, a manipulation of which in one direction serves to connect the operator's telephone set 27 in bridge of the cord-circuit and 90 a manipulation of which in the reversed direction serves to connect the ringing-generator 28 in bridge of the cord-circuit.

The cord-strand 24 is electrically continuous through supervisory relays 29 and 30, 95 these relays being shunted by a condenser

31, which serves to improve the transmission of voice-currents through the cord-circuit. A conductor 32 connects the common terminal of the relays 29 and 30 with the negative pole of 5 the common battery 10. A supervisory controlling-relay 33 is connected between the negative side of the battery 10 and the sleeve-strand 25 of the cord-circuit. The armature 34 of this supervisory controlling-relay when 10 attracted connects the positive pole of the battery 10 with supervisory signal-lamps 35 and 36, the circuits through these supervisory signal-lamps being respectively completed by the armatures 37 and 38 of the supervisory relays 15 when in their normal unattracted positions.

An impedance-coil 39 is connected between the negative pole of the battery 10 and the terminal of the generator 28, adapted for connection with the sleeve-strand 25 of the cord-20 circuit.

The operation of my improved system will now be made apparent.

A subscriber at substation A upon removing his receiver from its switch-hook closes a 25 continuous electrical circuit between the limbs 1 and 2 of the associated telephone-line, thereby permitting the passage of current from the battery 10 through the line-relay 9 to telephone-limbs 1 and 2 and through the two differentially-wound coils of the cut-off relay 16. A current flowing through this circuit causes 30 the energization of the line-relay 9 to attract its armature 18. The armatures 20 and 21 of the cut-off relay are not attracted by current flowing through this circuit, for the reason that the coils 14 and 15 are differentially wound, thereby producing no appreciable net energization of the core of the cut-off relay. The armature 20 when in its unattracted position 35 serves to close, in connection with the attracted armature 18, a local battery-circuit through the line-signal 19, causing this signal-lamp to glow, thereby notifying the operator that the subscriber at substation A desires connection 40 with some other subscriber. She thereupon inserts an answering-plug 22 within the corresponding answering-jack 12. A circuit of decreased resistance is thus closed through the coil 15 of the differential relay, this circuit 45 being traced as follows: from the negative pole of the battery 10, through the supervisory controlling-relay 33 to the sleeve of the plug 22, to the sleeve-contact 17 of the answering-jack 12, through the coil 15 of the differential relay to the positive pole of the battery 10. The increased flow of current 50 through the single coil 15 causes a net energization of the cut-off relay, thereby causing the attraction of its armatures 20 and 21. The 55 attraction of the armature 20 produces a break in the local circuit through the signal-lamp 19, whereby this lamp is extinguished. The attraction of the armature 21 causes the closure of a low-resistance circuit in shunt of the 60 winding 14 of the differential relay 16 and 65 winding 14 of the differential relay 16 and

also serves to directly connect the sleeve-contacts 17 with the limb 2 of the associated telephone-line without the intervention of inductive resistance. This feature of my invention gives a talking-circuit between the spring-jack and the limbs of the telephone-line, which being free from inductive resistances is peculiarly suitable for the transmission of voice-currents.

As previously pointed out, the insertion of 75 the plug 22 within the answering-jack 12 causes the closure of a circuit through the supervisory controlling-relay 33, whereupon the armature 34 is actuated to connect the positive side of the battery 10 with the lamps 80 35 and 36. The receiver at substation A being off its hook a circuit may be traced as follows: from the negative pole of the battery 10 through the relay 29, to the tip-strand 24 to the tip-spring 11 of the answering-jack 85 12, to the limb 1 of the telephone-line, through the transmitter 5 and primary coil 6, to the limb 2 of the telephone-line, through the short circuit in shunt of the coil 14, through the coil 15 of the differential relay to the positive 90 pole of the battery 10. The core of the supervisory relay 29 being thus energized causes the attraction of its armature 37, whereby a circuit through the supervisory signal-lamp 35 is opened. The operator manipulates her 95 ringing and listening key in the usual manner, connecting her telephone set in bridge of the cord-circuit, whereupon she ascertains the number of the substation with which the subscriber at substation A desires connection. Supposing this to be station B, she thereupon 100 inserts her calling-plug 23 within a multiple jack 13 and manipulates her ringing-key to connect the generator 28 across the cord-strands 24 and 25 leading to the calling-plug 105 23, whereby a signaling-current is caused to actuate the call-bell 4 at substation B. The insertion of the calling-plug 23 within the jack 13 causes the closure of a circuit through the coil 15 of the differential relay 16 associated with the line running to substation B. The armatures of this relay are thereby attracted, causing in one instance a break in the local circuit through the associated line signaling-lamp 19 and in the other instance the 110 closure of a shunt-circuit of low resistance about the winding 14 of its own cut-off relay. Upon answering the call the subscriber at substation B removes his receiver from its hook, thereby closing a circuit between the limbs of 115 the associated telephone-line, which circuit includes the battery 10 at the central station, the associated line-relay 9, and the coil 15 of the associated cut-off relay. The consequent 120 energization of the line-relay does not cause the illumination of the line signal-lamp 19, for the reason that the circuit through this lamp is open between the armature 20 of the 125 cut-off relay and its back contact.

It will be remembered that the insertion of 130

the answering-plug 22 in the answering-jack 12 caused the attraction of the armature 34, whereby a circuit is closed through the supervisory signaling-lamp 36 and the armature 38 of the supervisory relay 30. This lamp 36 will continue to glow until the removal of the receiver from the switch-hook at the called substation. The removal of this receiver causes the closure of a circuit through the supervisory relay 30 similar to that previously traced for the supervisory relay 29, whereupon the armature 38 is attracted from its back contact, thereby causing a break in the circuit through the supervisory signal-lamp 36. Thus upon the extinguishment of the lamp 36 the operator receives a signal that the subscriber at substation B has answered the calling-signal.

It may be pointed out that the function of the impedance 39 is to prevent the opening of the circuit through the coil 15 of the differential relay associated with the line to substation B upon the connection of the generator 28 with the cord-circuit. The circuit through the relay-coil 15 may be traced during the connection of the generator with the cord-circuit through the impedance-coil 39 instead of through the supervisory controlling-relay 33, while a generator-circuit in shunt of the circuit through the calling-bell 4 and the condenser 4 at substation B is provided. This shunt-circuit being of comparatively high resistance and high self-induction, the proper actuation of the calling-signal is not materially affected.

The means employed for testing a line to ascertain whether or not it is in use before a connection therewith is made may be described as follows: It will be seen that the test-thimbles associated with an idle line—for instance, the line leading to substation B—are normally connected with the positive grounded side of the battery 10 through the coil 15 of the differential relay. There being no current-flow through this idle line or the coil 15 the test-thimbles are normally of the same zero-potential as the grounded side of the battery 10. Upon the insertion of the calling-plug within any one of the multiple jacks associated with this line to substation B an electric circuit is closed through the associated cut-off-relay coil 15 and the supervisory controlling-relay 33. On account of the current flowing through this circuit there is a consequent rise in the potential of all of the thimbles of the multiple jacks connected with this circuit. Therefore when the tested line is busy or has already been called by another operator at some other one of the positions on the multiple board the test-thimbles associated with that line will have been raised in potential above the normal potential of the grounded side of the battery 10. The tip-contact of the calling-plug is used in connection with the test-thimbles of a called line to learn

whether or not the called line is busy. In order to test a line, the operator manipulates her listening-key, thereby connecting her telephone set in bridge of the cord-circuit and by means of the contact 40 connecting the tip-strand 24 of the cord-circuit with the ground through a test-winding 41, wound in inductive relation with the secondary winding of the induction-coil associated with the operator's telephone set. Furthermore, it will be seen that the manipulation of the listening-key breaks the connection through the supervisory relay 30 between the negative side of the battery 10 and the tip-strand of the cord-circuit. Thus, while the tip of the calling-plug is normally maintained at a potential equal to that of the negative side of the battery 10, upon the manipulation of the listening-key the part of the tip-strand of the cord-circuit leading to the tip-contact of the calling-plug 23 is connected through the test-winding 41 directly with the ground, to which is connected the positive side of the battery 10. Thus the tip-contact when applied to a test-thimble to ascertain the condition of a tested line is always at the zero potential of the ground. It will be remembered that in case the line to substation B is not busy or has not been called by an operator at some other position the test-thimbles are also at the zero potential of the ground. Thus upon contact being made between the tip of the calling-plug and the test-thimble there is no difference of potential to cause a current to flow. Therefore there is no current-flow through the test-winding 41 or a condenser-discharge to cause a click in the operator's receiver, which click, as is well understood by those skilled in the art, is commonly employed to notify the operator of the busy condition of a line. If, on the other hand, the tested line is connected with a cord-circuit at some operator's position, then the test-thimbles associated with that line will have been raised in potential above that of the ground. Therefore upon contact being made between the test-thimble and the tip-contact of the calling-plug a current will be caused to flow through the tip-strand of the cord-circuit and the connected test-winding 41 to the grounded side of the battery 10. The flow of current through the test-winding 41 of course produces a click in the operator's telephone, notifying her of the busy condition of the tested line.

While I have herein shown and described one particular embodiment of my invention, it will be apparent to those skilled in the art that many modifications therein may well be employed without departing from the spirit of my invention. I do not, therefore, wish to limit myself to the precise disclosure herein set forth; but,

Having described my invention, I claim as new and desire to secure by Letters Patent—

1. In a telephone-exchange system, the com-

bination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in one limb of said line, and a test-contact connected to the common terminal of the windings of said differential cut-off relay.

15 2. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings permanently serially included in one limb of said line, means whereby the connection of 20 said cord connecting apparatus with said line closes a circuit of decreased resistance through one winding of said cut-off relay to cause an actuation thereof, and a test-contact connected to the common terminal of the windings of 25 said differential cut-off relay.

30 said differential cut-off relay.

3. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay

35 40 having two differential windings serially included in one limb of said line, means whereby the connection of said cord connecting apparatus with said line closes a circuit of decreased resistance through one winding of said cut-off relay to cause an actuation thereof, and a test-contact connected to the common terminal of the windings of said differential cut-off relay.

45

4. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings permanently serially included in one limb of said line, and a test-contact connected to the common terminal of the windings of said differential cut-off relay.

5. In a telephone-exchange system, the combination with a common source of current at the exchange, one terminal of said source being permanently connected to ground, of a

telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in the limb of said line connected to the grounded side of said source of current, and a test-contact connected to the common terminal of the windings of said differential cut-off relay. 70 75

6. In a telephone-exchange system, the combination with a common source of current at the exchange, one terminal of said source being permanently connected to ground, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings permanently serially included in the limb of said line connected to the grounded side of said source of current, means whereby the connection of said cord connecting apparatus with said line closes a circuit of decreased resistance through one winding of said cut-off relay to cause an actuation thereof, and a test-contact connected to the common terminal of the windings of said differential cut-off relay. 80 85 90 95

7. In a telephone-exchange system, the combination with a common source of current at 100 the exchange, one terminal of said source being permanently connected to ground, of a telephone-line extending by its limbs from the terminals of said source of current to a substation, means at the substation adapted 105 to close an electrical connection between said limbs, cord connecting apparatus at the exchange adapted to connect said line with another for conversation, a cut-off relay having two differential windings serially included in 110 the limb of said line connected to the grounded side of said source of current, means whereby the connection of said cord connecting apparatus with said line closes a circuit of decreased resistance through one winding of 115 said cut-off relay to cause an actuation thereof, and a test-contact connected to the common terminal of the windings of said differential cut-off relay.

8. In a telephone-exchange system, the combination with a common source of current at the exchange, one terminal of said source being permanently connected to ground, of a telephone-line extending by its limbs from the terminals of said source of current to a substation, means at the substation adapted to close an electrical connection between said limbs, cord connecting apparatus at the exchange adapted to connect said line with another for conversation, a cut-off relay having

two differential windings permanently serially included in the limb of said line connected to the grounded side of said source of current, and a test-contact connected to the common 5 terminal of the windings of said differential cut-off relay.

9. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 10 said line with another for conversation, a cut-off relay having two differential windings permanently serially included in one limb of said line, a line-relay permanently serially included in the other limb of said line, a line-signal 15 jointly controlled by said line and cut-off relays, means whereby the connection of said cord connecting apparatus with said line closes a circuit of decreased resistance through one winding of said cut-off relay to cause an 20 actuation thereof, and a test-contact connected to the common terminal of the windings of said differential cut-off relay.

10. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 30 said line with another for conversation, a cut-off relay having two differential windings serially included in one limb of said line, a line-relay serially included in the other limb of 35 said line, a line-signal jointly controlled by said line and cut-off relays, means whereby the connection of said cord connecting apparatus with said line closes a circuit of decreased resistance through one 40 winding of said cut-off relay to cause an actuation thereof, and a test-contact connected to the common terminal of the windings of said differential cut-off relay.

45 40

11. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 50 said line with another for conversation, a cut-off relay having two differential windings permanently serially included in one limb of said line, a line-relay permanently serially included in the other limb of 55 said line, a line-signal jointly controlled by said line and cut-off relays, and a test-contact connected to the common terminal of the windings of said differential cut-off relay.

60 55

12. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 65 said line with another for conversation, a cut-off relay having two differential windings serially included in one limb of said line, a line-relay serially included in the other limb of said line, a line-signal jointly controlled by said line and cut-off relays, and a test-contact connected to the common terminal of the windings of said differential cut-off relay.

70 75

13. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 80 said line with another for conversation, a cut-off relay having two differential windings permanently serially included in one limb of said line, means whereby the connection of said cord connecting apparatus with said line closes a circuit of decreased resistance through one 85 winding of said cut-off relay to cause an actuation thereof, a test-contact connected to the common terminal of the windings of said differential cut-off relay, and switching means controlled by said cut-off relay adapted upon 90 an actuation of said relay to connect said test-contact to a limb of said line through a low-resistance circuit in shunt of one winding of said cut-off relay.

95 100

14. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect 105 said line with another for conversation, a cut-off relay having two differential windings serially included in one limb of said line, means 110 whereby the connection of said cord connecting apparatus with said line closes a circuit of decreased resistance through one winding of said cut-off relay to cause an actuation thereof, a test-contact connected to the common 115 terminal of the windings of said differential cut-off relay, and switching means controlled by said cut-off relay adapted upon 120 an actuation of said relay to connect said test-contact to a limb of said line through a low-resistance 125 circuit in shunt of one winding of said cut-off relay.

130

15. In a telephone-exchange system, the combination with a common source of current at the exchange, one terminal of said source be-

- ing permanently connected to ground, of a telephone-line extending by its limbs from the terminals of said source of current to a substation, means at the substation adapted to close 5 an electrical connection between said limbs, cord connecting apparatus at the exchange adapted to connect said line with another for conversation, a cut-off relay having two differential windings permanently serially included 10 in the limb of said line connected to the grounded side of said source of current, means whereby the connection of said cord connecting apparatus with said line closes a circuit of decreased resistance through one winding of 15 said cut-off relay to cause an actuation thereof, a test-contact connected to the common terminal of the windings of said differential cut-off relay, and switching means controlled by 20 said cut-off relay adapted upon an actuation of 25 said relay to connect said test-contact to a limb of said line through a low-resistance circuit in shunt of one winding of 30 said cut-off relay.
16. In a telephone-exchange system, the combination with a common source of current 35 at the exchange, one terminal of said source being permanently connected to ground, of a telephone-line extending by its limbs from the terminals of said source of current to a substation, means at the substation adapted to close 40 an electrical connection between said limbs, cord connecting apparatus at the exchange adapted to connect said line with another for conversation, a cut-off relay having two differential windings serially included in the limb 45 of said line connected to the grounded side of said source of current, means whereby the connection of said cord connecting apparatus with said line closes a circuit of decreased resistance through one winding of 50 said cut-off relay to cause an actuation thereof, a test-contact connected to the common terminal of the windings of said differential cut-off relay, and switching means controlled by 55 said cut-off relay adapted upon an actuation of 60 said relay to connect said test-contact to a limb of said line through a low-resistance circuit in shunt of one winding of 65 said cut-off relay.
17. In a telephone-exchange system, the combination with a common source of current 70 at the exchange, of a telephone-line extending by its limbs from the terminals of said source of current to a substation, means at the substation adapted to close an electrical connection between said limbs, cord connecting apparatus at the exchange adapted to connect 75 said line with another for conversation, a cut-off relay having two differential windings permanently serially included in one limb of said line, a line-relay permanently serially included 80 in the other limb of said line, a line-signal jointly controlled by said line and cut-off relays, means whereby the connection of said cord connecting apparatus with said line closes a circuit of decreased resistance through one winding of 85 said cut-off relay to cause an actuation thereof, a test-contact connected to the common terminal of the windings of said differential cut-off relay, and switching means controlled by 90 said cut-off relay adapted upon an actuation of 95 said relay to connect said test-contact to a limb of said line through a low-resistance circuit in shunt of one winding of 100 said cut-off relay.
18. In a telephone-exchange system, the combination with a common source of current 105 at the exchange, of a telephone-line extending by its limbs from the terminals of said source of current to a substation, means at the substation adapted to close an electrical connection between said limbs, cord connecting apparatus at the exchange adapted to connect 110 said line with another for conversation, a cut-off relay having two differential windings serially included in one limb of said line, a line-relay serially included in the other limb of 115 said line, a line-signal jointly controlled by said line and cut-off relays, means whereby the connection of said cord connecting apparatus with said line closes a circuit of decreased resistance through one winding of 120 said cut-off relay to cause an actuation thereof, a test-contact connected to the common terminal of the windings of said differential cut-off relay, and switching means controlled by 125 said cut-off relay adapted upon an actuation of said relay to connect said test-contact to a limb of said line including said cut-off relay through a low-resistance circuit in shunt of one winding of 130 said cut-off relay.
20. In a telephone-exchange system, the combination with a common source of current 135

at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in one limb of said line, a line-relay permanently serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact permanently connected with the limb of the line including said line-relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

21. In a telephone - exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings permanently serially included in one limb of said line, a line-relay serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact permanently connected with the limb of the line including said line-relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

22. In a telephone - exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings permanently

serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact connected with the limb of the line including said line-relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

23. In a telephone - exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in one limb of said line, a line-relay serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact permanently connected with the limb of the line including said line-relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

24. In a telephone - exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in one limb of said line, a line-relay permanently serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact connected with the limb of the line including said line-

relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

25. In a telephone-exchange system, the combination with a common source of current at the exchange, of a telephone-line extending by its limbs from the terminals of said source of current to a substation, means at the substation adapted to close an electrical connection between said limbs, cord connecting apparatus at the exchange adapted to connect said line with another for conversation, a cut-off relay having two differential windings serially included in one limb of said line, a line-relay serially included in the other limb of said line, a line-signal jointly controlled by said line and cut-off relays, means whereby the connection of said cord connecting apparatus with said line closes a circuit of decreased resistance through one winding of said cut-off relay to cause an actuation thereof, a spring-jack having one contact connected with the limb of the line including said line-relay, a test-contact connected to the common terminal of the windings of said differential cut-off relay, and switching means controlled by said cut-off relay adapted upon an actuation of said relay to connect said test-contact to the limb of said line including said cut-off relay through a low-resistance circuit in shunt of one winding of said cut-off relay.

26. In a telephone-exchange system, the combination with a common source of current at the exchange, of a telephone-line extending by its limbs from the terminals of said source to a substation, means at the substation adapted to close an electrical connection between said limbs, cord connecting apparatus at the central exchange adapted to connect said line with another for conversation, a cut-off relay having two differential windings serially included in one limb of said line, means whereby the connection of said cord connection apparatus with said line closes a circuit of decreased resistance through one winding of said cut-off relay to cause an actuation thereof, a test-contact normally connected with one limb of the telephone-line through one of said windings, and an armature for said cut-off relay adapted upon actuation of said relay to connect said test-contact directly with said limb.

27. In a telephone-exchange system, the combination with a common source of current at the exchange, of a telephone-line extending by its limbs from the terminals of said source to a substation, means at the substation adapted to close an electrical connection between said limbs, cord connecting apparatus at the central exchange adapted to con-

nect said line with another for conversation, a cut-off relay having two differential windings serially included in one limb of said line, means whereby the connection of said cord connecting apparatus with said line closes a circuit of decreased resistance through one winding of said cut-off relay to cause an actuation thereof, a test-contact normally connected with one limb of the telephone-line through one of said windings, and means upon connection of said cord connecting apparatus with said line for directly connecting said test-contact with said limb.

28. In a telephone-exchange system, the combination with a common source of current at the exchange, of a telephone-line extending by its limbs from the terminals of said source to a substation, means at the substation adapted to close an electrical connection between said limbs, cord connecting apparatus at the central exchange adapted to connect said line with another for conversation, a cut-off relay having two differential windings serially included in one limb of said line, means whereby the connection of said cord connection apparatus with said line closes a circuit of decreased resistance through one winding of said cut-off relay to cause an actuation thereof, a test-contact normally connected with one limb of the telephone-line through one of said windings, means upon connection of said cord connecting apparatus with said line for directly connecting said test-contact with said limb, and a line-relay permanently included in the other limb of said line.

29. In a telephone-exchange system, the combination with a common source of current at the exchange, of a telephone-line extending by its limbs from the terminals of said source to a substation, means at the substation adapted to close an electrical connection between said limbs, cord connection apparatus at the central exchange adapted to connect said line with another for conversation, a cut-off relay having two differential windings serially included in one limb of said line, means whereby the connection of said cord connection apparatus with said line closes a circuit of decreased resistance through one winding of said cut-off relay to cause an actuation thereof, a test-contact normally connected with one limb of the telephone-line through one of said windings, an armature for said cut-off relay adapted upon actuation of said relay to connect said test-contact directly with said limb, and a line-relay permanently included in the other limb of said line.

30. In a telephone-exchange system, the combination with a common source of current at the exchange, of a telephone-line extending by its limbs from the terminals of said source to a substation, means at the substation adapted to close an electrical connection between said limbs, cord connecting apparatus at the

- central exchange adapted to connect said line with another for conversation, a cut-off relay having two differential windings serially included in one limb of said line, means whereby the connection of said cord connecting apparatus with said line closes a circuit of decreased resistance through one winding of said cut-off relay to cause an actuation thereof, a test-contact normally connected with one limb 5 of the telephone-line through one of said windings, a line-relay permanently included in the other limb of said line, two armatures for said cut-off relay and an armature for said line-relay, a local line-signal circuit adapted to include 10 said line-relay armature and one of said cut-off-relay armatures, and means upon connection of said cord connecting apparatus with said line for causing actuation of said cut-off relay to attract its armatures, whereby said 15 local circuit is opened by one of said cut-off-relay armatures and whereby said other cut-off-relay armature closes a short circuit about said winding, whereby said test-contact is connected directly with the line-limb.
- 20 31. In a telephone-exchange system, the combination with a common source of current at the exchange, of a telephone-line extending by its limbs from the terminals of said source of current to a substation, switching mechanism at the substation adapted to close a circuit through said limbs, cord connecting apparatus at the exchange adapted to connect said line with another for conversation, a line-relay permanently serially included in one 25 limb of said line and controlled by switching mechanism at the substation, a cut-off relay having two differential windings permanently serially included in the other limb of said line, a line-signal jointly controlled by said line and 30 cut-off relays, a spring-jack having a contact permanently connected with said first limb, and a test-contact permanently connected with the common terminal of the differential windings of said cut-off relay, means whereby the 35 insertion of a plug of said cord connecting apparatus in said spring-jack closes a circuit of decreased resistance through one winding of said cut-off relay to cause a net energization and actuation thereof, and switching means 40 controlled by said cut-off relay adapted upon a net energization of said relay to connect said test-contact to a limb of said line through a low-resistance circuit in shunt of one winding of said cut-off relay.
- 45 32. In a telephone-exchange system, the combination with a common source of current at the exchange having one terminal permanently connected to ground, of a telephone-line extending by its limbs from the terminals 50 of said source of current to a substation, switching mechanism at the substation adapted to close a circuit through said limbs, cord connecting apparatus at the exchange adapted to connect said line with another for conversation, a line-relay permanently serially included 55 in the line-limb which is connected with the terminal of the common source of current not connected to the ground and controlled by switching mechanism at the substation, a cut-off relay having two differential windings permanently serially included in the other limb of said line, a line-signal jointly controlled by said line and cut-off relays, a spring-jack having a contact permanently connected with said first limb, and a test-contact permanently connected with the common terminal of the differential windings of said cut-off relay, means whereby the insertion of a plug of said cord connecting apparatus in said spring-jack closes a circuit of decreased resistance through one 60 winding of said cut-off relay to cause a net energization and actuation thereof, and switching means controlled by said cut-off relay adapted upon a net energization of said relay to connect said test-contact to a limb of said line through a low-resistance circuit in shunt of one winding of said cut-off relay.
- 65 33. In a telephone-exchange system, the combination with a common source of current at the exchange, of a telephone-line extending by its limbs from the terminals of said source to a substation, cord connecting apparatus at the exchange for connecting said line with another, a cut-off relay having two differential windings serially included in one limb of said line, an armature for said relay, a spring-jack contact permanently connected directly with one limb of said line, a test-contact normally connected with the other limb of said line through one of said relay-windings, and means upon connection of said cord connecting apparatus with said line for causing attraction of said armature to cause a short circuit about said winding to connect said test-contact directly with said other limb.
- 70 34. In a telephone-exchange system, the combination with a common source of current at the exchange, of a telephone-line extending by its limbs from the terminals of said source to a substation, cord connecting apparatus at the exchange for connecting said line with another, a cut-off relay having two differential windings permanently serially included in one limb of said line, an armature for said relay, a spring-jack contact permanently connected directly with one limb of said line, a test-contact normally connected with the other limb of said line through one of said relay-windings, and means upon connection of said cord connecting apparatus with said line for causing attraction of said armature to cause a short circuit about said winding to connect said test-contact directly with said other limb.
- 75 35. In a telephone-exchange system, the combination with a common source of current at the exchange, of a telephone-line extending by its limbs from the terminal of said source to a substation, cord connecting apparatus at the exchange, a cut-off relay permanently serially included in one limb of said line, a spring-

jack contact permanently connected directly with one limb of said line, a test-contact permanently connected with the other limb of said line through part of said relay-winding, an armature for said relay, and means upon connection of said cord connecting apparatus with said line for causing attraction of said armature to close a short circuit about said part of

the winding, whereby said test-contact is connected directly with said other limb. 10

In witness whereof I hereunto subscribe my name this 31st day of January, A. D. 1903.

HARRY G. WEBSTER.
